(57) **ABSTRACT**

An artificial magnet conductor includes a dielectric medium, basic cells, each being formed on a side of a front surface of the dielectric medium, and including a conductive patch pattern and a conductive loop pattern formed with a predetermined gap with the conductive patch pattern, a frequency selective surface on which the basic cells are periodically arranged on the front surface of the dielectric medium, and a conductive layer formed on a side of a rear surface of the dielectric medium. A phase change from an incident wave to a reflected wave with respect to the dielectric medium is set as an addition value in which a first phase change in the gap is added to a second phase change between the basic cell of

**ARTIFICIAL MAGNET CONDUCTOR,
ANTENNA REFLECTOR, AND METHOD
FOR CALCULATING THICKNESS OF
DIELECTRIC MEDIUM**

TECHNICAL FIELD

The present invention relates to an artificial magnet conductor which reflects an electromagnetic wave in a specific frequency, an antenna reflector which uses the artificial magnet conductor, and a method for calculating a thickness of a dielectric medium of the artificial magnet conductor.

BACKGROUND ART

In the related art, it is not considered that an antenna for a broad bandwidth is used in a situation in which directivity is required. However, recently, the situation in which a broadband antenna with directivity is required has increased. In order for the broadband antenna to have an appropriate directivity, a reflection plate which reflects an electromagnetic wave is generally used. The reflection plate is provided in a location which is generally separated from the antenna by $\lambda/4$ (λ is a wavelength of an electromagnetic wave which is used) (refer to, for example, Patent Literature 1). That is, when an antenna element and a ground element (ground plate) are combined together to operate, for example, in a case where antenna characteristics such as emission efficiency or gain increase, setting of a gap between the antenna element and the ground plate is very important.

Specifically, if a material of the ground element is assumed to be a complete electric conductor, a condition for obtaining the best antenna characteristics is that a gap between the antenna element and the ground element has a length of a quarter of a wavelength of a wave which is used. In order to satisfy the condition, the antenna has a limitation of minimizing a size thereof.

Accordingly, a low profile antenna which employs a structure of an artificial magnet conductor that is called an electromagnetic band gap (EBG) structure is proposed. That is, the EBG structure is a structure in which unit cell patterns of a square shorter than an emission wavelength of an antenna are arranged in a matrix. The unit cell patterns formed of a metal are formed on a surface of a dielectric substrate which configures the artificial magnet conductor, a ground metal plate is formed on a rear surface of the dielectric substrate, and an artificial magnet conductor which is close to a complete magnetic body and has high surface impedance is formed (refer to, for example, Patent Literature 2).

As described above, a method for designing an artificial magnet conductor which reflects a predetermined frequency by mainly using the artificial magnet conductor for the reflection plate is disclosed (refer to, for example, Non Patent Literature 1 and Non Patent Literature 2).

Non Patent Literature 1 discloses a method for appropriately designing a distance between a frequency selective surface (FSS) and a ground plate, in an artificial magnet conductor in which there is air ($\epsilon_r=1$) between the FSS and the ground plate.

Non Patent Literature 2 describes design of an artificial magnet conductor according to an FSS which uses a dielectric layer.

20 SUMMARY OF INVENTION

Technical Problem

25 However, each of Non Patent Literature 1 and Non Patent Literature 2 has a problem in which, although a reflection plate is actually designed by using an artificial magnet conductor using a described physical model, frequency characteristics of a designed reflection plate do not coincide with frequency characteristics of the reflection plate which is actually produced, and thus, accuracy of reflection frequency characteristics decreases. Patent Literature 1 also has the problem in which the frequency characteristics of the designed reflection plate do not coincide with the frequency characteristics of the actually produced reflection plate, and Non Patent Literature 1 and Non Patent Literature 2 have the same problem.

30 The present invention is made in view of the situations, and provides an artificial magnet conductor with frequency characteristics which are closer to frequency characteristics of a design value and has high accuracy, compared to the related art, an antenna reflector which uses the artificial magnet conductor, and a method for calculating a thickness of a dielectric medium of the artificial magnet conductor.

45

Solution to Problem

50 In order to achieve the problem as mentioned above, an artificial magnet conductor according to an aspect of the present invention includes: a dielectric medium; basic cells, each being formed on a side of a front surface of the dielectric medium, and including a conductive patch pattern and a conductive loop pattern that is formed with a predetermined gap with the conductive patch pattern; a frequency selective surface on which the basic cells are periodically arranged on the front surface of the dielectric medium; and a conductive layer that is formed on a side of a rear surface of the dielectric medium, and a phase change from an incident wave to a reflected wave with respect to the dielectric medium is set as an addition value in which a first phase change in the gap is added to a second phase change between the basic cell of the dielectric medium and the conductive layer, and a thickness of the dielectric medium is set based on the addition value.

55 60 65 60 In the artificial magnet conductor according to an aspect of the present invention, the dielectric medium may be a dielectric substrate.

In the artificial magnet conductor according to an aspect of the present invention, the thickness of the dielectric medium may be set by a predetermined expression using the addition value.

In the artificial magnet conductor according to an aspect of the present invention, the addition value may be an addition phase change amount in which the second phase change which is a phase rotation amount is added to the first phase change caused by capacitance which is formed by the gap.

In the artificial magnet conductor according to an aspect of the present invention, the predetermined expression may be an expression that subtracts the first phase change from a phase change amount which is obtained based on an S parameter of the frequency selective surface and is required for the dielectric medium, calculates the second phase change which is obtained as the subtraction results, and calculates the thickness of the dielectric medium from the second phase change.

In the artificial magnet conductor according to an aspect of the present invention, the frequency selective surface may be formed such that one of the conductive patch pattern and the conductive loop pattern has inductive reactance, and the other has capacitive reactance, at a predetermined frequency bandwidth.

In the artificial magnet conductor according to an aspect of the present invention, the thickness of the dielectric medium may be set such that the artificial magnet conductor has frequency characteristics corresponding to a plurality of frequencies, change curves of a dielectric thickness and a phase in each of the plurality of frequencies are obtained, and the phase is within $\pm 45\%$ of the entirety of the plurality of frequencies.

In the artificial magnet conductor according to an aspect of the present invention, the thickness of the dielectric medium that is determined by the predetermined expression may be greater than a distance of the gap when the thickness is calculated.

In the artificial magnet conductor according to an aspect of the present invention, the conductive patch pattern may be formed in a polygon, and the frequency characteristics of the frequency selective surface may be adjusted by further increasing the number of apexes by cutting regions of apex portions of the polygon in a direction perpendicular to a line connecting the apexes to a center of the polygon.

In an antenna reflector according to an aspect of the present invention, the artificial magnet conductor is used as a reflection plate.

In the antenna reflector according to an aspect of the present invention, the artificial magnet conductor may be provided to be detachable.

An aspect of the present invention provides a method for calculating a thickness of a dielectric medium of an artificial magnet conductor including a dielectric medium; basic cells, each being formed on a side of a front surface of the dielectric medium, and including a conductive patch pattern and a conductive loop pattern that is formed with a predetermined gap with the conductive patch pattern; a frequency selective surface on which the basic cells are periodically arranged on the front surface of the dielectric medium; and a conductive layer that is formed on a side of a rear surface of the dielectric medium, the method including: setting a phase change from an incident wave to a reflected wave with respect to the dielectric medium, as an addition value in which a first phase change in the gap is added to a second phase change between the basic cell of the dielectric

medium and the conductive layer; and calculating the thickness of the dielectric medium based on the addition value.

Advantageous Effects of Invention

As described above, according to the present invention, a phase change from an incident wave to a reflected wave with respect to a dielectric medium is set as an addition value in which a first phase change in the gap is added to a second phase change between basic cell and a ground plate in the dielectric medium, a thickness of the dielectric medium is obtained to be produced by inserting the addition value into a predetermined expression, and thus, it is possible to obtain an accurate thickness of the dielectric medium corresponding to the frequency characteristics, and to configure an artificial magnet conductor having frequency characteristics closer to frequency characteristics of a design value, compared to the related art.

BRIEF DESCRIPTION OF DRAWINGS

FIG. 1 illustrates a configuration example of an artificial magnet conductor (metamaterial) according to the present embodiment.

FIG. 2 is a conceptual view illustrating a configuration example of a reflection plate for antenna which uses the artificial magnet conductor according to the present embodiment.

FIG. 3 is a conceptual view illustrating another configuration example of an antenna device which uses the artificial magnet conductor 10 of FIG. 1 as a reflection plate.

FIG. 4 is a conceptual view illustrating a relationship between a reflected wave of an incident electromagnetic wave and an S parameter of an FSS 11, in the artificial magnet conductor 10.

FIG. 5 is a diagram illustrating a path of the reflected wave when the electromagnetic wave is incident perpendicularly to a surface on which the FSS 11 of the artificial magnet conductor 10 is formed.

FIG. 6 is a diagram illustrating a correspondence relationship, which is denoted on a complex plane, between a phase rotation amount and a reflection phase, with respect to a surface of an FSS 11, in a state where an electric field of an incident electromagnetic wave is referred to as E_{in} .

FIG. 7 is a graph illustrating a correspondence relationship between a frequency, which is obtained by Expression (8), of the electromagnetic wave that is incident on the artificial magnet conductor 10, and a phase change amount ϕ_e of a dielectric substrate 12.

FIG. 8 is a conceptual view illustrating a relationship between the reflected wave and the S parameter of the FSS 11 in the artificial magnet conductor 10 of the electromagnetic wave which is incident by a modified physical model according to the present embodiment.

FIG. 9 is a diagram illustrating a gap between each pattern of a patch 101 and a loop 102 which configure the artificial magnet conductor 10 according to the present embodiment.

FIG. 10 is a conceptual view illustrating the phase change amount ϕ_e caused by a capacitance C_g .

FIG. 11 is a diagram illustrating a relationship between a thickness of the dielectric substrate 12 and a phase rotation amount which are obtained by Expression (19).

FIG. 12 is a diagram illustrating each correspondence relationship between a frequency and a reflection phase according to calculation results obtained by Expression (21) and results of electromagnetic field simulation, for comparison.

FIG. 13 is a graph illustrating a relationship between a thickness (required substrate thickness) d of the required dielectric substrate 12 and a frequency of the electromagnetic wave, which are obtained by Expression (23).

FIG. 14 is a graph illustrating a relationship between a reflection phase and the thickness (required substrate thickness) d of the dielectric substrate 12 that is required, which are obtained by Expression (23).

FIG. 15 is a diagram illustrating a relationship between the thickness d of the dielectric substrate 12 obtained by Expression (23), and a distance of a gap between a pattern of the patch 101 and a pattern of the loop 102 when the thickness is obtained.

FIG. 16 is a conceptual view illustrating modification of pattern shapes of the patch 101 and the loop 102 which configure a basic cell 100 of the FSS 11.

FIG. 17 is a diagram illustrating frequency characteristics of a filter with a pattern shape of each of the basic cells 100 illustrated in FIG. 16(a) and FIG. 16(b), for comparison.

FIG. 18 is a radiation pattern diagram illustrating directivity when the artificial magnet conductor 10 which is produced in correspondence with 2.45 GHz is used as a reflection plate.

FIG. 19 is a radiation pattern diagram illustrating directivity of an antenna in a case where the artificial magnet conductor 10 (AMC, complete magnetic conductor) which is produced in correspondence with 2.45 GHz is used as a reflection plate, and in a case where a complete magnetic conductor (PEC) such as copper is used as a reflection plate.

FIG. 20 is a view illustrating concept of obtaining a phase change amount between an incident wave and a reflected wave of the artificial magnet conductor according to the present invention.

DESCRIPTION OF EMBODIMENTS

Hereinafter, an embodiment of the present invention will be described with reference to the drawings.

FIG. 1 illustrates a configuration example of an artificial magnet conductor (metamaterial) according to the present embodiment. Dimension of the present embodiment is just an example, and is for making electromagnetic waves with frequencies of a 2.4 GHz bandwidth and a 5 GHz bandwidth pass through, as will be described below. In a case where other frequencies pass through, dimension of each unit naturally changes depending upon a target frequency. FIG. 1 specifies a configuration of FIG. 20 which is a conceptual view of a basic configuration of an artificial magnet conductor according to the present invention, in accordance with the embodiment which will be described below.

FIG. 1(a) illustrates a plan view of the artificial magnet conductor. As illustrated in FIG. 1(a), a basic cell 100 is configured with a patch 101, and a loop 102 which is formed to surround the patch 101. The artificial magnet conductor (metamaterial) 10 has a surface on which the basic cells 100, each side having a length of 19 mm, are periodically arranged in a matrix with an interval (1.0 mm in the present embodiment). The basic cells 100 may be obliquely arranged. In the present embodiment, the artificial magnet conductor 10 is configured with nine basic cells 100 of 3 (row)×3 (column) as an example, and has a square, each side having a length of 59 mm. The artificial magnet conductor 10 functions with characteristics which are set, if the basic cells 100 have the number of arrays of 2×2 or more. The patch 101 is a pattern (patch pattern) which is formed of a conductor layer with a predetermined thickness, such as a metal, and has, for example, an octagon which is formed by

cutting apexes of the square, each side having a length of 11 mm, in a direction of a line perpendicular to a line connecting the apex to the center of the square. In addition, the patches 101 are arranged in a matrix on a surface of the dielectric substrate 12 (will be described below) and are periodically arranged with a predetermined distance to other patches 101 adjacent to each other. The loops 102 are formed to surround outer circumferences of the patches 101 on the same surface as the patch 101, and have a pattern (loop pattern) which is formed of a layer of a conductor (conductor layer) having the same shape as the patch 101 with a predetermined width. Here, the loop 102 has a square, each side having a length of 18 mm, and there is a gap of predetermined distance (1.0 mm in the present embodiment) between a side of an inner circumference of the loop and a side of the patch 101. The loop 102 is formed to surround the patch 101, the inner circumference of the loop corresponds to an outer circumference of the patch 101, and the loop has a gap of the predetermined distance with the patch.

FIG. 1(b) is a cross-sectional view of the artificial magnet conductor taken along line 1B-1B of FIG. 1(a). A frequency selective surface (FSS) 11 is formed on a rear surface of a surface on which a ground plate 13 is formed in the dielectric substrate 12. In addition, FSS 11 is a surface layer of the artificial magnet conductor 10 which is configured with the respective patterns of the patch 101 and the loop 102. The dielectric substrate 12 is a substrate of dielectric substance with a relative dielectric constant ϵ_r and a thickness t . The ground plate 13 is a ground plate (ground surface) which is formed of a conductor such as a metal. Generally, the artificial magnet conductor 10 which is used as a reflection plate with a predetermined frequency is produced by adjusting each of filter characteristics of FSS 11 and a thickness d of the dielectric substrate 12.

FIG. 2 is a conceptual view illustrating a configuration example of an antenna device which uses the artificial magnet conductor 10 of FIG. 1 as a reflection plate. FIG. 2 is a view that is viewed from a side of the antenna device. In a supporting body 200, fixing walls 201 of a protrusion shape are formed perpendicularly to a surface 200A of the supporting body 200 so as to face each other on a surface 200B opposite to the surface 200A of the supporting body 200. Slits 202 in which depth directions of grooves are parallel to the surface 200A are provided on surfaces of the fixing walls 201 which face each other. End portions of the artificial magnet conductor 10 which is used as a reflector (reflection plate) are inserted into the slits 202, and the artificial magnet conductor 10 is fixed to the supporting body 200.

In addition, an opening 203 is formed in a central portion of the supporting body 200, and an antenna substrate 300 is disposed on the surface 200A to cover the opening 203. A distance between a surface of the antenna substrate 300 and the surface of the artificial magnet conductor 10 which face each other is set to, for example, 5 mm to 15 mm. The distance between the surfaces of the antenna substrate 300 and the artificial magnet conductor 10 which face each other is set by directivity of the antenna device. Here, in the antenna substrate 300 and the artificial magnet conductor 10, a surface from which an electromagnetic wave is emitted and a surface which emits an electromagnetic wave are disposed in parallel to each other. In addition, a surface, which faces the antenna substrate 300, of the artificial magnet conductor 10 is a surface on which the FSS 11 is formed. In addition, the electromagnetic wave which is emitted from the antenna substrate 300 is reflected by the

artificial magnet conductor **10** and is emitted from the antenna device in an R direction.

FIG. 3 is a conceptual view illustrating another configuration example of the antenna device which uses the artificial magnet conductor **10** of FIG. 1 as the reflection plate. FIG. 3 is a view which is viewed from a side of the antenna device. A hole **250** which passes through a supporting body **211** is formed in the supporting body **211**. Slits **212** in which depth directions of grooves are parallel to surface **211A** are provided on side walls, which face each other, of an inner surface of the hole **250**. The end portions of the artificial magnet conductor **10** which is used as a reflection plate are inserted into the slits **212**, and the artificial magnet conductor **10** is fixed to the supporting body **211**. In addition, an antenna substrate **310** is disposed on the surface **211A** to cover the hole **250** of the supporting body **211**. A distance between a surface of the antenna substrate **310** and the surface of the artificial magnet conductor **10** which face each other is set to, for example, 5 mm to 15 mm in the same manner as in FIG. 3. The distance between the surfaces of the antenna substrate **300** and the artificial magnet conductor **10** which face each other is set by directivity of the antenna device. In addition, the surface, which faces the antenna substrate **310**, of the artificial magnet conductor **10** is a surface on which the FSS **11** is formed. The electromagnetic wave which is emitted from the antenna substrate **310** is reflected by the artificial magnet conductor **10** and is emitted from the antenna device in the R direction.

<Design of Artificial Magnet Conductor>

In the present embodiment, filter characteristics of the FSS **11** on which the basic cells **100** are arranged, that is, each of S parameters S_{11} (reflection coefficient), S_{12} (transmission coefficient), S_{21} (transmission coefficient), and S_{22} (reflection coefficient), which are used for calculation in designing the artificial magnet conductor **10** hereinafter, are obtained by actual measurement or simulation. Here, the simulation is simulation of electromagnetic field-electromagnetic field analysis which uses a finite difference time domain method (FDTD) or a finite element method. Description is previously made, but in the present embodiment, perfect magnetic conductor (PMC) characteristics appear at a specific frequency, the distance d between the ground plate **13** and the FSS **11** is set, and thereby the artificial magnet conductor **10** is designed.

In the present embodiment, a design method for the artificial magnet conductor **10** with the PMC characteristics at each frequency of specific two frequencies, for example, 2.4 GHz and 5 GHz will be hereinafter described.

FIG. 4 is a conceptual view illustrating a relationship between a reflected wave of an incident electromagnetic wave and the S parameter of the FSS **11**, in the artificial magnet conductor **10**. In FIG. 4, the FSS **11** is formed on the front surface of the dielectric substrate **12**, and the ground plate **13** is formed on the rear surface thereof. A reflection coefficient of an electromagnetic wave of the front surface of the dielectric substrate **12** on which the FSS **11** is formed is S_{11} , and a transmission coefficient of an electromagnetic wave which passes through the inside of the dielectric substrate **12** from the front surface is S_{21} . In addition, a transmission coefficient of an electromagnetic wave which is incident on the dielectric substrate **12**, is reflected by the ground plate **13**, and passes through the front surface, is S_{12} , and a reflection coefficient of an electromagnetic wave which is reflected from an interface between the FSS **11** and the dielectric substrate **12** is S_{22} . A basic model (Non Patent Literature 2) describes that a phase change occurs only in the phase rotation amount ϕ_e (second phase change), an electric

field is incident on the ground plate **13**, and a reflection phase thereof becomes $-\pi$ (rad), in the dielectric substrate **12**.

In addition, in the present embodiment, approximation ray theory in which logic is simple is used as a design method. By using the approximation ray theory, characteristics of an electromagnetic wave can be directly calculated by adding a full electromagnetic field to another electromagnetic wave. In the present embodiment, the approximation ray theory of the related approximation ray theory is extended by a physical model that the inventor designs, and a calculation expression which performs design of an artificial magnet conductor with more accuracy is realized, which will be described below.

FIG. 5 is a diagram illustrating a path of the reflected wave when the electromagnetic wave (plane wave) is incident perpendicularly to a surface on which the FSS **11** of the artificial magnet conductor **10** is formed. In FIG. 5, the FSS **11** is formed on the front surface of the dielectric substrate **12**, and the ground plate **13** is formed on the rear surface thereof, in the same manner as in FIG. 4. A reflected wave R_0 with an amplitude of $|S_{11}|$ times an amplitude of an incident electromagnetic wave is reflected by the FSS **11** of the artificial magnet conductor **10**. The reflected wave R_0 is not reflected from an interface between the dielectric substrate **12** and the ground plate **13** even once. That is, the reflected wave R_0 is reflected from the interface between the dielectric substrate **12** and **13** zero times.

In addition, a transmission wave which is $|S_{21}|$ times the incident electromagnetic wave is incident on the dielectric substrate **12**. The incident electromagnetic wave is reflected by the interface between the dielectric substrate **12** and the ground plate **13**, and is incident on the interface between the FSS **11** and the dielectric substrate **12** again. Here, if the electromagnetic wave passes through the interface between the FSS **11** and the dielectric substrate **12**, the electromagnetic wave becomes a reflected wave R_1 . In the reflected wave R_1 , a transmission wave which is $|S_{21}| \cdot |S_{12}|$ times the incident electromagnetic wave is emitted into the air. The reflected wave R_1 is reflected from the interface between the dielectric substrate **12** and the ground plate **13** once.

Meanwhile, the incident electromagnetic wave is reflected from the interface between the dielectric substrate **12** and the ground plate **13**, and is reflected from the interface between the FSS **11** and the dielectric substrate **12**. In addition, the electromagnetic wave is reflected from the interface between the dielectric substrate **12** and the ground plate **13** again, and is incident on the interface between the FSS **11** and the dielectric substrate **12**. Here, if the electromagnetic wave passes through the interface between the FSS **11** and the dielectric substrate **12**, the electromagnetic wave becomes the reflected wave R_2 . The reflected wave R_2 is reflected from the interface between the dielectric substrate **12** and the ground plate **13** twice. In addition, if the electromagnetic wave which is incident on the artificial magnet conductor **10** is reflected from the interface between the dielectric substrate **12** and the ground plate **13** N times, the reflected wave becomes a reflected wave R_N .

In a case where the number of reflections from the interface between the dielectric substrate **12** and the ground plate **13** which are described above is $N=0$, 1, and 2, an electric field E_0 of the reflected wave R_0 , an electric field E_1 of the reflected wave R_1 , and an electric field E_2 of the reflected wave R_2 are respectively represented by Expression (1), Expression (2), and Expression (3) which are described below. In the present embodiment, j is an imaginary unit.

[Expression 1]

$$E_0 = |S_{11}| e^{j\phi_{11}} \quad (1)$$

In Expression (1), a phase ϕ_{11} denotes a reflection phase when the electromagnetic wave is reflected to the air, at the interface between the FSS 11 and the dielectric substrate 12. S_{11} is a reflection coefficient.

[Expression 2]

$$E_1 = |S_{21}||S_{12}| e^{j(\phi_{21} + \phi_{12} + 2\phi_e - \pi)} \quad (2)$$

In Expression (2), a phase ϕ_{21} denotes a transmission phase when the electromagnetic wave passes through the dielectric substrate 12 side from the FSS 11 side, at the interface between the FSS 11 and the dielectric substrate 12. In addition, a phase ϕ_{12} denotes a transmission phase when the electromagnetic wave passes through the FSS 11 side from the dielectric substrate 12 side, at the interface between the FSS 11 and the dielectric substrate 12. The phase rotation amount ϕ_e is a phase rotation amount between the FSS 11 and the dielectric substrate 12. S_{21} and S_{12} are transmission coefficients. In addition, the phase change amount ϕ_e is a phase rotation amount which is generated in accordance with a distance between the FSS 11 and the dielectric substrate 12, that is, the thickness d of the dielectric substrate 12.

[Expression 3]

$$E_2 = |S_{21}||S_{12}||S_{22}| e^{j(\phi_{22} + \phi_{21} + \phi_{12} + 4\phi_e - 2\pi)} \quad (3)$$

In Expression (3), a phase ϕ_{22} denotes a reflection phase when the electromagnetic wave is reflected to the dielectric substrate 12 side, at the interface between the FSS 11 and the dielectric substrate 12. In addition, a phase ϕ_{21} denotes a transmission phase when the electromagnetic wave passes through the dielectric substrate 12 side from the FSS 11 side, at the interface between the FSS 11 and the dielectric substrate 12. A phase ϕ_{12} denotes a transmission phase when the electromagnetic wave passes through the FSS 11 side from the dielectric substrate 12 side, at the interface between the FSS 11 and the dielectric substrate 12. The phase change amount ϕ_e is a phase rotation amount between the FSS 11 and the dielectric substrate 12. S_{21} and S_{12} are transmission coefficients. S_{11} and S_{22} are reflection coefficients.

In addition, in a case where the number of reflections from the interface between the dielectric substrate 12 and the ground plate 13 is one or more, a combined electric field of the entire reflected waves from the reflected wave R_0 to the reflected wave R_N is represented as geometric series which are represented by a first term E_1 and a geometric ratio r . The geometric ratio r is represented by following Expression (4).

[Expression 4]

$$r = |S_{22}| e^{j(\phi_{22} + 2\phi_e - \pi)} \quad (4)$$

By using the geometric ratio r of Expression (4) described above, a combined electric field E_{total} of the entire reflected waves from the reflected wave R_0 to the reflected wave R_N is represented by following Expression (5).

[Expression 5]

$$E_{total} = E_0 + \sum_{n=1}^N E_n = E_0 + \frac{E_1(1 - r^N)}{1 - r} \quad (5)$$

In Expression (5), N becomes ∞ (infinity). Thereby, r^N becomes zero, and Expression (5) can be represented by following Expression (6).

[Expression 6]

$$E_{total} = E_0 + \frac{E_1}{1 - r} \quad (6)$$

Here, a declination angle of the electric field E_{total} becomes a reflection phase ϕ_{FSS} of the artificial magnet conductor 10.

FIG. 6 is a diagram illustrating a correspondence relationship, which is denoted on a complex plane, between the reflection phase ϕ_{FSS} and the phase rotation amount ϕ_{shift} , with respect to the front surface of an FSS 11, in a state where an electric field of an incident electromagnetic wave is referred to as E_{in} . A vertical axis is an imaginary number axis ($\text{Im}(E_{total})$) and a horizontal axis is a real number axis ($\text{Rm}(E_{total})$).

If the electromagnetic field E_{in} is one on the complex plane, when the declination angle of the electric field E_{total} is zero, the declination angle of the electromagnetic field E_{total} coincides with the phase rotation amount ϕ_{FSS} . At this time, the phase rotation amount ϕ_{shift} becomes zero, and the artificial magnet conductor 10 denotes characteristics of a complete magnetic conductor.

In addition, as described above, the phase rotation amount ϕ_{shift} has positive and negative values corresponding to a rotation direction of the reflection phase ϕ_{FSS} , as illustrated in FIG. 6. Hence, when an imaginary portion $I_m(E_{total})=0$, a real portion $R_e(E_{total})>0$, the phase rotation amount ϕ_{shift} becomes zero. In addition, it can be seen that, when the number of rotations N is large enough, the real portion $R_e(E_{total})$ substantially has a positive value, and thus, $E_{total}=0$ as condition in which $\arg(E_{total})=0$.

If Expression (1), Expression (2), Expression (3), and $E_{total}=0$ are inserted into Expression (6), following Expression (7) is obtained.

[Expression 7]

$$2\phi_e = \arg\left(\frac{|S_{11}| e^{j\phi_{11}}}{|S_{21}||S_{12}| e^{j(\phi_{21} + \phi_{12})} - |S_{11}||S_{22}| e^{j(\phi_{11} + \phi_{22})}}\right) \quad (7)$$

Accordingly, the phase rotation amount ϕ_e incident on the dielectric substrate 12 can be represented by following Expression (8).

[Expression 8]

$$\phi_e = \pm \frac{1}{2} \arg\left(\frac{|S_{11}| e^{j\phi_{11}}}{|S_{21}||S_{12}| e^{j(\phi_{21} + \phi_{12})} - |S_{11}||S_{22}| e^{j(\phi_{11} + \phi_{22})}}\right) \quad (8)$$

In a case of the aforementioned physical model (that is, basic model), the calculated phase rotation amount ϕ_e corresponds to the phase rotation amount ϕ_{shift} . The phase change amount ϕ_e (that is, the phase rotation amount ϕ_{shift}) required for the dielectric substrate 12 is obtained based on the S parameters (S_{11} , S_{12} , S_{21} , and S_{22}) of the FSS 11 in FIG. 4.

FIG. 7 is a graph illustrating a correspondence relationship between a frequency, which is obtained by Expression

(8), of the electromagnetic wave that is incident on the artificial magnet conductor **10** and the phase change amount ϕ_e of the dielectric substrate **12**. In FIG. 7, a vertical axis denotes a reflection phase change amount (Required Phase Shift, unit is deg.), a horizontal axis denotes a frequency (Frequency, unit is GHz) of the incident electromagnetic wave. As illustrated by the graph of FIG. 7, plus and minus phase change amounts ϕ_e are all "0" at 3 GHz.

In addition, the phase change amount ϕ_e of the dielectric substrate **12** can be represented by following Expression (9).

[Expression 9]

$$\phi_e = -\frac{2\pi f d \sqrt{\epsilon_{eff}}}{c} \quad (9)$$

In Expression (9), f denotes a frequency of an incident electromagnetic wave, d denotes a thickness of the dielectric substrate **12**, ϵ_{eff} denotes an effective relative dielectric constant, and c denotes speed of light.

Here, the effective relative dielectric constant ϵ_{eff} can be represented by following Expression (10). In Expression (10), ϵ_r denotes relative dielectric constant, W denotes a width of a pattern of the patch **101**, d denotes a thickness of the dielectric substrate **12**, and t denotes a thickness of each of the patch **101** and the loop **102**.

[Expression 10]

$$\epsilon_{eff} = \frac{\epsilon_r + 1}{2} + \frac{\epsilon_r - 1}{2} F\left(\frac{W}{d}\right) - \frac{\epsilon_r - 1}{4.6} \frac{t}{d} \quad (10)$$

In addition, $F(W/d)$ in Expression (10) is represented by following Expression (11).

[Expression 11]

$$F\left(\frac{W}{d}\right) = \frac{1}{\sqrt{1 + 12 \frac{d}{W}}} \quad (11)$$

$$\frac{W}{d} \geq 1$$

However, it is confirmed that the phase change amount ϕ_e which is obtained by calculation of Expression (6), Expression (9), Expression (10), and Expression (11) which are described above does not coincide with the results of the electromagnetic field simulation obtained by using a finite element method. Hence, actually, it is considered that a phase change more than the phase change amount which is represented by Expression (9) occurs. Accordingly, as described below, study of a physical model of a reflection system of the electromagnetic wave in the artificial magnet conductor **10** has been performed.

Here, the basic cell **100** of the FSS **11** according to the present embodiment is configured with each of the patch **101** and the loop **102**, as illustrated in FIG. 1. The patch **101** of the basic cell **100** is formed in an inner side of the loop **102**, an area thereof is AP ($=116.5 \text{ mm}^2$), and an outer circumference thereof is L_p ($=40.5 \text{ mm}$). In the loop **102** of the

basic cell **100**, an area is AL ($=165.125 \text{ mm}^2$), and an outer circumference is AN L_1 ($=72 \text{ mm}$). Here, if a wavelength shortening rate η is considered, a parallel resonance frequency f_p of a structure of the patch **101** is represented by Expression (12), and a parallel resonance frequency f_L of a structure of the loop **102** is represented by Expression (13). In Expression (12) and Expression (13), c is speed of light, and $c=3\times10^8 \text{ m/s}$.

[Expression 12]

$$f_p = \frac{c \times \eta}{L_p} \quad (12)$$

[Expression 13]

$$f_L = \frac{c \times \eta}{L_1} \quad (13)$$

The wavelength shortening rate η of Expression (12) and Expression (13) is obtained by following Expression (14).

[Expression 14]

$$\eta = \frac{1}{\sqrt{\epsilon_{eff}}} \quad (14)$$

If the width w of the pattern of the patch **101** is 18 mm and the thickness t of the pattern of the patch **101** is 0.035 mm, the effective relative dielectric constant ϵ_{eff} which is obtained by Expression (10) and Expression (11) is 4.05. The wavelength shortening rate η is calculated by inserting the effective relative dielectric constant ϵ_{eff} into Expression (14). In addition, each of the parallel resonance frequency f_p and the parallel resonance frequency f_L is obtained by inserting the calculation results into each of Expression (12) and Expression (13). As a result, the parallel resonance frequency f_p of 3.68 GHz is obtained from Expression (12), and the parallel resonance frequency f_L is obtained from Expression (13). As a result, the parallel resonance frequency f_p of 2.07 GHz is obtained from Expression (12).

Here, in a case where a frequency of an incident electromagnetic wave is lower than the parallel resonance frequency f_p of the patch **101**, the patch **101** has characteristics of capacitive reactance. In the same manner, in a case where the frequency of the incident electromagnetic wave is lower than the parallel resonance frequency f_L of the loop **102**, the loop **102** has characteristics of capacitive reactance. In addition, in a case where the frequency of the incident electromagnetic wave is higher than the parallel resonance frequency f_p of the patch **101** and is equal to or lower than double of the parallel resonance frequency f_p , the patch **101** becomes inductive reactance. In the same manner, in a case where the frequency of the incident electromagnetic wave is higher than the parallel resonance frequency f_L of the loop **102** and is equal to or lower than double of the parallel resonance frequency f_L , the loop **102** becomes inductive reactance.

In addition, in a case where the frequency of the incident electromagnetic wave is equal to or higher than double of the parallel resonance frequency f_p of the patch **101** and is equal to or lower than triple of the parallel resonance frequency f_p , the patch **101** becomes capacitive reactance. In the same manner, in a case where the frequency of the incident electromagnetic wave is equal to or higher than double of the

13

parallel resonance frequency f_L of the loop 102 and is equal to or lower than triple of the parallel resonance frequency f_P , the loop 102 becomes capacitive reactance.

That is, a relationship in a case where the patch 101 has the characteristics of capacitive reactance can be represented by the following expression, if the frequency of the incident electromagnetic wave is referred to as f .

$$f < f_P, 2f_P < f < 3f_P$$

In the same manner, a relationship in a case where the loop 102 has the characteristics of capacitive reactance can be represented by the following expression, if the frequency of the incident electromagnetic wave is referred to as f .

$$f < f_L, 2f_L < f < 3f_L$$

In addition, a relationship in a case where the patch 101 has the characteristics of inductive reactance can be represented by the following expression, if the frequency of the incident electromagnetic wave is referred to as f .

$$f_P < f < 2f_P$$

In the same manner, a relationship in a case where the loop 102 has the characteristics of inductive reactance can be represented by the following expression, if the frequency of the incident electromagnetic wave is referred to as f .

$$f_L < f < 2f_L$$

Here, in a case where the frequency is 2.4 GHz to 2.5 GHz, the parallel resonance frequency f_P is 2.07 GHz, and the parallel resonance frequency f_P is 3.68 GHz. Accordingly, the patch 101 has the characteristics of capacitive reactance, and the loop 102 has the characteristics of inductive reactance.

Meanwhile, in a case where the frequency is 5 GHz to 6 GHz, the parallel resonance frequency f_P is 2.07 GHz, and the parallel resonance frequency f_P is 3.68 GHz. Accordingly, the patch 101 has the characteristics of inductive reactance, and the loop 102 has the characteristics of capacitive reactance.

In addition, it is known that an evanescent wave is generated on the FSS 11 with finite impedance, in a structure of a sheet shape configured by each of the FSS 11 and the ground plate 13 which have finite impedance, and the dielectric substrate 12 (for example, refer to Hiroyuki SHINODA: "Speed of Light Network Which is Formed on Surface of Material", Measurement and Control, VOL. 46, NO. 2, 2007).

The evanescent wave is generated in any one pattern of the patch 101 and the loop 102 which have characteristics of inductive reactance by the incident electromagnetic wave and is changed with respect to the other pattern having characteristics of capacitive reactance.

That is, the evanescent wave generated by the pattern of the inductive reactance is transferred from the pattern of inductive reactance to the pattern of capacitive reactance through a gap between the patterns of the patch 101 and the loop 102. In addition, the evanescent wave is incident on the dielectric substrate 12 from the pattern of the capacitive reactance. As a result, modification is not made in the basic model, but made in a physical model of a reflection system of the electromagnetic wave of the artificial magnet conductor 10, by taking into account a phase change in the gap between the patterns of the patch 101 and the loop 102.

FIG. 8 is a conceptual view illustrating a relationship between the reflected wave and the S parameter of the FSS 11 in the artificial magnet conductor 10 of the electromagnetic wave which is incident by a modified physical model

14

according to the present embodiment. In FIG. 8, the FSS 11 is formed on the front surface of the dielectric substrate 12, and the ground plate 13 is formed on the rear surface thereof. A reflection coefficient of the electromagnetic wave of the front surface on which the FSS 11 of the dielectric substrate 12 is formed is S_{11} , and a transmission coefficient of the electromagnetic wave which passes through the inside of the dielectric substrate 12 from the front surface thereof is S_{21} . In addition, a transmission coefficient of the electromagnetic wave which is incident on the dielectric substrate 12, is reflected by the ground plate 13, and passes through the front surface, is S_{12} , and a reflection coefficient of the electromagnetic wave which is reflected from the interface between the FSS 11 and the dielectric substrate 12 is S_{22} .

In addition, the evanescent wave generated in the pattern of the inductive reactance is transferred to the pattern of the capacitive reactance, and thereafter, the evanescent wave is incident on the dielectric substrate 12. Here, capacitance of a gap between (that is, between the patch 101 and the loop 102) the patterns is referred to as C_g . In addition, a phase change in the gap having the capacitance C_g is referred to as a phase change ϕ_g (first phase change). It is considered that the phase change ϕ_g of the aforementioned evanescent wave becomes an error of the basic model. That is, it is considered that a phase change larger than the phase change amount which is represented by Expression (9) corresponds to the phase change ϕ_g .

FIG. 9 is a diagram illustrating the gap between each pattern of the patch 101 and the loop 102 which configure the artificial magnet conductor 10 according to the present embodiment. In FIG. 9, the FSS 11 is formed on the front surface of the dielectric substrate 12, and the ground plate 13 is formed on the rear surface thereof. A width of the pattern of the patch 101 in the FSS 11 of the dielectric substrate 12 is W_P , and a width of the pattern of the loop 102 is W_L . In addition, a distance of a gap between the pattern of the patch 101 and the pattern of the loop 102 is g . An addition distance which is obtained by adding the width of the pattern of 30 101, the width of the pattern of the loop 102, and the distance g of the gap together is a . ϵ_r is a relative dielectric constant of a dielectric substrate, and ϵ_0 is a relative dielectric constant of air. V is a potential difference between the loop 102 and the patch 101.

The capacitance C_g which is generated in the gap between the pattern of the patch 101 and the pattern of the loop 102 can be represented by two-dimensional electrostatic field distribution as described below. That is, in the physical model modified in accordance with the present embodiment, distribution ψ of an electric flux between the pattern of the patch 101 and the pattern of the loop 102, that is, in the gap 40 can be represented by following Expression (15).

[Expression 15]

$$\Psi = \text{Im} \left\{ \frac{\epsilon_0(1 + \epsilon_r)V}{\pi} \cos^{-1} \left(\frac{a}{g} \right) \right\} = \frac{\epsilon_0(1 + \epsilon_r)V}{\pi} \cosh^{-1} \left(\frac{\frac{W_P}{2} + W_L + g}{g} \right) \quad (15)$$

In Expression (15), a is the addition distance, g is a distance of the gap between each pattern of the patch 101 and the loop 102, and V is a potential difference between the loop 102 and the patch 101. In addition, ϵ_r is a relative dielectric constant of a dielectric substrate, and ϵ_0 is a relative dielectric constant of air.

In addition, in a case where a uniform electric flux is distributed on one side (length W_P+2W_L+2g) of the pattern of the loop **102**, the capacitance C_g of a gap between the pattern of the patch **101** and the pattern of the loop **102** is represented by following Expression (16) from $C=Q/V$.

[Expression 16]

$$C_g = \frac{(W_P+2W_L+2g)\epsilon_0(1+\epsilon_r)}{\pi} \cosh^{-1}\left(\frac{W_P+2W_L+2g}{2g}\right) \quad (16)$$

FIG. 10 is a conceptual view illustrating the phase change ϕ_g caused by the capacitor C_g . A phase change amount of the evanescent wave which is an electromagnetic wave generated by the capacitance C_g is obtained from a reflection phase (reflection coefficient S_{11}) when the capacitance of the gap is regarded as a two-terminal network. That is, the phase change ϕ_g caused by the capacitance C_g of the gap is obtained by $\arg(S_{11})$. The phase change ϕ_g is obtained by each of following Expression (17) and Expression (18). Here, Expression (17) represents the reflection coefficient S_{11} .

[Expression 17]

$$S_{11} = \frac{1 - (\omega C_g Z_0)^2}{1 + (\omega C_g Z_0)^2} - j \frac{2\omega C_g Z_0}{1 + (\omega C_g Z_0)^2} \quad (17)$$

[Expression 18]

$$\phi_g = \frac{1}{2} \arg(S_{11}) = \frac{1}{2} \tan^{-1}\left(\frac{-2\omega C_g Z_0}{1 - (\omega C_g Z_0)^2}\right) \quad (18)$$

In each of Expression (17) and Expression (18), Z_0 is characteristic impedance, and ω is an angular frequency of an electromagnetic wave which is propagated. C_g is capacitance of the gap between the patterns of the patch **101** and the loop **102**. In each of Expression (17) and Expression (18), it is assumed that $Z_0=50\Omega$.

In a case where the phase change ϕ_g in the gap between the patterns of the patch **101** and the loop **102** is considered, the phase rotation amount ϕ_{shift} is obtained by following Expression (19).

[Expression 19]

$$\phi_{shift} = \phi_e + \phi_g = -\frac{2\pi f d \sqrt{\epsilon_{eff}}}{c} + \frac{1}{2} \tan^{-1}\left(\frac{-2\omega C_g Z_0}{1 - (\omega C_g Z_0)^2}\right) \quad (19)$$

In Expression (19), ϵ_{eff} denotes an effective relative dielectric constant, and f denotes a frequency of an electromagnetic wave. c denotes speed of light. Z_0 is characteristic impedance, and ω is an angular frequency of an electromagnetic wave which is propagated. C_g is capacitance of the gap between the patterns of the patch **101** and the loop **102**.

FIG. 11 is a diagram illustrating a relationship between the thickness of the dielectric substrate **12** and the phase rotation amount, which are obtained by Expression (19). In FIG. 11, a vertical axis denotes the phase rotation amount ϕ_{shift} and a horizontal axis denotes the thickness d of the dielectric substrate **12**. A solid line denotes a relationship in a case where the frequency of the electromagnetic wave is $f=2.45$ GHz, and a dashed line denotes a relationship

(change curve) in a case where the frequency of the electromagnetic wave is $f=5.44$ GHz.

In addition, if Expression (6) is rewritten by using Expression (19), the electric field E_{total} of a reflected wave is represented by following Expression (20).

[Expression 20]

$$E_{total} = E_0 + \frac{E_1}{1-r} = |S_{11}|e^{j\phi_{11}} + \frac{|S_{21}||S_{12}|e^{j(\phi_{21}+\phi_{12}+2\phi_e+2\phi_g-\pi)}}{1-|S_{22}|e^{j(\phi_{22}+2\phi_g+2\phi_e-\pi)}} \quad (20)$$

15 In Expression (20), a reflection phase ϕ_{AMC} of the entire artificial magnet conductor **10** can be obtained by performing calculation, using following Expression (21).

20 [Expression 21]

$$\phi_{AMC} = \arg(E_{total}) = \tan^{-1}\left(\frac{\text{Im}(E_{total})}{\text{Re}(E_{total})}\right) \quad (21)$$

30 FIG. 12 is a diagram illustrating a correspondence relationship between a frequency and a reflection phase according to calculation results obtained by Expression (21) and the results of the electromagnetic field simulation, for comparison. In FIG. 12, a vertical axis denotes the reflection phase ϕ_{AMC} , and a horizontal axis denotes a frequency of an electromagnetic wave.

35 As can be seen from FIG. 12, results obtained by a basic model do not substantially coincide with the results of the electromagnetic field simulation (FEM simulation). The basic model is a model in which the phase change ϕ_g caused by the capacitance G_g of the gap is not considered but only the phase change amount ϕ_e in the dielectric substrate **12** represented by Expression (9) is considered.

40 However, it can be seen that the results obtained by Expression (21) of the modified model according to the present embodiment exactly coincides with the results of the electric field simulation, compared with the basic model.

45 In Expression (21) described above, a design expression of the thickness d of the dielectric substrate **12** can be obtained by setting $E_{total}=0$ as a condition that a reflection phase is set to "0". Here, if the phase change amount ϕ_e which is calculated by Expression (8) is set to the phase rotation amount ϕ_{shift} , following Expression (22) is obtained.

55 [Expression 22]

$$\phi_{shift} = \pm \frac{1}{2} \arg\left(\frac{|S_{11}|e^{j\phi_{11}}}{|S_{21}||S_{12}|e^{j(\phi_{21}+\phi_{12})} - |S_{11}||S_{22}|e^{j(\phi_{11}+\phi_{22})}}\right) \quad (22)$$

60 In addition, following Expression (23) which obtains the thickness of the dielectric substrate **12** is obtained by inserting Expression (22) described above into Expression (19). In addition, in Expression (23), an absolute value is taken such that the required phase rotation amount ϕ_{shift} necessarily has a negative value, and a negative sign is attached thereto.

[Expression 23]

$$d = \frac{c}{4\pi f \sqrt{\epsilon_{eff}}} \left(-\tan^{-1} \left(\frac{|S_{11}|e^{j\phi_{11}}}{|S_{21}||S_{12}|e^{j(\phi_{21}+\phi_{12})} - |S_{11}||S_{22}|e^{j(\phi_{11}+\phi_{22})}} \right) - \tan^{-1} \left(\frac{-2\omega_g Z_o}{1 - (\omega_g Z_o)} \right) \right) \quad (23)$$

In a case where the artificial magnet conductor **10** having characteristics of a complete magnetic conductor only at a single frequency is produced, the thickness d of the dielectric substrate **12** corresponding to the frequency of the electromagnetic wave which is reflected may be calculated by using Expression (23). Here, the thickness d of the dielectric substrate **12** is determined based on an addition phase change amount which is obtained by adding the phase change amount ϕ_e caused by the FSS **11** (frequency selective surface) to a phase change caused by the capacitance which is formed by the gap between the pattern of the patch **101** and the pattern of the loop **102** which are formed on the FSS **11**, using Expression (23). That is, the phase change amount ϕ_e (thickness phase change) which is determined only by the thickness of the dielectric substrate that is obtained by subtracting the phase change ϕ_g caused by C_g from the phase rotation amount ϕ_{shift} required for the dielectric substrate **12** based on the S parameters of the FSS **11**, and the thickness d of the dielectric substrate **12** is calculated from the phase change amount ϕ_e , using Expression (23).

FIG. 13 is a graph illustrating a relationship between the thickness (required substrate thickness) d of the required dielectric substrate **12** and the frequency of the electromagnetic wave, which are obtained by Expression (23). In FIG. 13, a vertical axis denotes the thickness of the dielectric substrate **12**, and a horizontal axis denotes the frequency of the electromagnetic wave. Here, d in a frequency region in which the thickness d of the dielectric substrate **12** is negative is not able to be produced. In a case of the present embodiment, a study on the thickness d of the dielectric substrate **12** for obtaining characteristics of a complete magnetic conductor in two frequency bandwidths different from each other is performed in relation to the artificial magnet conductor **10**.

FIG. 14 is a graph illustrating a relationship between the reflection phase ϕ_{shift} (reflection phase at fixed frequency) at a fixed frequency and the thickness (required substrate thickness) d of the dielectric substrate **12** that is required, which are obtained by Expression (23). In FIG. 15, a vertical axis denotes the reflection phase ϕ_{shift} , and a horizontal axis denotes the thickness d of the dielectric substrate **12**. In addition, a solid line denotes a change curve showing correspondence between the reflection phase ϕ_{shift} and the thickness d in a case where the frequency of electromagnetic wave is 2.45 GHz, and a dashed line denotes a change curve showing correspondence between the reflection phase ϕ_{shift} and the thickness d in a case where the frequency of electromagnetic wave is 5.44 GHz.

It is hard to determine the thickness d of the dielectric substrate **12** in FIG. 13. Accordingly, in FIG. 14, the thickness d of the dielectric substrate **12** changes, and correspondence between the thickness d of the dielectric substrate **12** and the reflection phase ϕ_{shift} is obtained as results in which the reflection phase is obtained by Expression (23). As can be seen from FIG. 4, if the thickness d of the dielectric substrate **12** is in a range of 0.5 mm to 2.3 mm,

reflection phase ϕ_{shift} of the electromagnetic wave at the frequency of each of 2.45 GHz and 5.44 GHz is within $\pm 45^\circ$, and thus, the characteristics of the artificial magnet conductor **10** can approach the characteristics of a complete magnetic conductor.

FIG. 15 is a diagram illustrating a relationship between the thickness d (Substrate Thickness) of the dielectric substrate **12** obtained by Expression (23), and the distance (Gap between Patch and Loop) of a gap between the pattern of the patch **101** and the pattern of the loop **102** when the thickness d is obtained. In FIG. 15, a vertical axis denotes the thickness d of the dielectric substrate **12**, and a horizontal axis denotes the distance of the gap between the pattern of the patch **101** and the pattern of the loop **102**. In addition, a solid line is a curve obtained in correspondence with the frequency of 2.45 GHz, while a dashed line is a curve obtained in correspondence with the frequency of 5.44 GHz.

Here, as illustrated in FIG. 14, if the thickness d of the dielectric substrate **12** is in a range of 0.5 mm to 2.3 mm, the reflection phase ϕ_{shift} of the electromagnetic wave at frequencies of each of 2.45 GHz and 5.44 GHz is within $\pm 45^\circ$. It can be seen that, in a range in which the thickness d of the dielectric substrate **12** is 0.5 mm to 2.3 mm, the thickness d of the dielectric substrate **12** at frequencies of each of 2.45 GHz and 5.44 GHz is greater than the distance of the gap between the pattern of the patch **101** and the pattern of the loop **102** when the thickness is obtained. That is, in the graph of FIG. 15, the distance of the gap corresponding to an arbitrary thickness d in a range of 0.5 mm to 2.3 mm is shorter than the thickness d of the dielectric substrate **12**, in coordinates on the curves of each of 2.45 GHz and 5.44 GHz.

Hence, when the thickness d of the dielectric substrate **12** is calculated by Expression (23), the thickness d of the dielectric substrate **12** is greater than the distance of the corresponding gap on the curve, in a range in which the thickness d of the dielectric substrate **12** is 0.5 mm to 2.3 mm. In addition, reflection phase ϕ_{shift} of the electromagnetic wave at frequencies of each of 2.45 GHz and 5.44 GHz is within $\pm 45^\circ$, and the characteristics of the artificial magnet conductor **10** can approach the characteristics of a complete magnetic conductor, in a relationship between the thickness d of the dielectric substrate **12** and the distance of the gap.

Meanwhile, in a case where the artificial magnet conductor **10** having characteristics of a complete magnetic conductor only at a single frequency is produced, the thickness d in which reflection phase ϕ_{shift} becomes 0° is set, and thereby, the complete magnetic conductor can be obtained. For example, in a case where the artificial magnet conductor becomes the complete magnetic conductor at a frequency of 2.45 GHz in a frequency of an incident electromagnetic wave, the thickness d of the dielectric substrate **12** becomes 1.5 mm, and thereby the artificial magnet conductor **10** of a complete magnetic conductor whose reflection phase is 0° at 2.45 GHz can be produced. In addition, in a case where the artificial magnet conductor becomes the complete magnetic conductor at a frequency of 5.44 GHz in a frequency of an incident electromagnetic wave, the thickness d of the dielectric substrate **12** becomes 2.3 mm, and thereby the artificial magnet conductor **10** of a complete magnetic conductor whose reflection phase is 0° at 5.44 GHz can be produced.

Accordingly, for example, a set value of the thickness d of the dielectric substrate **12** is set to 1.6 mm close to an average value of the dielectric substrate **12** in which a phase becomes 0° at frequencies of each of 2.45 GHz and 5.44 GHz. Thereby, in the present embodiment, in a case of being used as a reflection plate for an antenna, the thickness d of

the dielectric substrate in which the reflection phase is within $\pm 45^\circ$ at two frequencies can be simply set, and a reflection pale which satisfies both to the two frequencies can be produced, based on Expression (23).

As described above, according to the present embodiment, as the thickness d of the dielectric substrate **12** is set by using a physical model in which the phase change ϕ_g occurring when an incident electromagnetic wave is propagated from an inductive pattern to a capacitive pattern as an evanescent wave is added to the phase rotation amount ϕ_e of the dielectric substrate **12**, and by using an expression which calculates the thickness of the dielectric substrate **12**, the produced artificial magnet conductor **10** can have characteristics closer to a design value, and the artificial magnet conductor **10** which copes with a specific frequency bandwidth with high accuracy can be provided.

<Fine Adjustment of Frequency>

Next, description will be made with respect to adjustment of frequency characteristics which is made by changing a pattern shape, in a case where pattern shapes of the patch **101** and the loop **102** which configure the FSS **11** are configured by a polygon having apexes a triangle or more. The frequency characteristics denotes a frequency in which the reflection coefficient S_{11} of the S parameter has a minimum value.

The adjustment of frequency characteristics is made by cutting (chamfering) a region of apexes by using a line perpendicular to lines connecting the apexes to the center of the polygon, in a pattern shape of the patch **101** which is configured by a polygon.

That is, the pattern shape of the patch **101** is changed to a polygonal shape with many apexes. In changing the pattern of the patch **101**, adjustment of decreasing a frequency of the reflection coefficient S_{11} of filter characteristics of the FSS **11** is made by increasing apexes of the pattern of the patch **101**. At this time, a gap of a distance between a side of the inner circumference of the loop **102** surrounding the patch **101** and a side of the outer circumference of the patch **101** is the same at any location. Accordingly, the loop **102** is chamfered such that sides of the inner circumference thereof corresponds to sides of the outer circumference of the patch **101**.

FIG. 16 is a conceptual view illustrating modification of the pattern shapes of the patch **101** and the loop **102** which configure a basic cell **100** of the FSS **11**. Numeric values of FIG. 16 denote dimension (unit is mm). FIG. 16(a) illustrates the basic cell **100** which is configured by the patch **101** with a pattern shape of a square. FIG. 16(b) illustrates the basic cell **100** which is configured by the patch **101** with an octagonal pattern shape by cutting regions of apexes of the patch **101** of FIG. 16(a).

In FIG. 16(a), an outer circumference of the patch **101** forms a square, and thus, an inner circumference of the loop **102** forms a square different from the patch **101**. Meanwhile, in FIG. 16(b), an outer circumference of the patch **101** forms an octagon, and thus, an inner circumference of the loop **102** forms an octagon different from the patch **101**.

FIG. 17 is a diagram illustrating frequency characteristics of a filter having a pattern shape of each of the basic cells **100** illustrated in FIG. 16(a) and FIG. 16(b), for comparison. In FIG. 17, a vertical axis denotes phase characteristics (S_{11} phase) of the reflection coefficient S_{11} , and a horizontal axis denotes a frequency of an incident electromagnetic wave. The frequency characteristics are formed by the FSS **11** in which the basic cells **100** are arranged in a 3x3 matrix. A dashed line illustrates a relationship between the reflection coefficient S_{11} in a case of the patch **101** having a rectangular

pattern shape illustrated in FIG. 16(a) and a frequency of an incident electromagnetic wave. Meanwhile, a solid line illustrates a relationship between the reflection coefficient S_{11} in a case of the patch **101** having an octagonal pattern shape illustrated in FIG. 16(a) and a frequency of an incident electromagnetic wave. As can be seen from FIG. 17, the reflection coefficient S_{11} has minimum value at a lower frequency by performing chamfering. Hence, the patch is close to a ring shape by being gradually polygonised by chamfering, and thereby the phase characteristics of the reflection coefficient S_{11} are changed to a low frequency side. Accordingly, the frequency characteristics of the reflection coefficient S_{11} can be finely adjusted.

There are a triangle, a pentagon, a hexagon, an octagon, a decagon, or the like as a polygon which is used frequently and differently. However, it is considered that, as the number of chamfering is reduced, the patch becomes a shape close to a ring depending on a size of the patch, and a decrease of the frequency is saturated in a polygon having a certain number of apexes.

As described above, according to the present embodiment, chamfering of the patch **101** is performed from the basic cell **100**, and chamfering of a shape of the inner circumference of the loop **102** is performed so as to correspond to the outer circumference of the chamfered patch **101**, and thereby the phase characteristics of the reflection coefficient S_{11} can be corrected (adjusted) toward a low frequency side without changing an area of the basic cell **100**.

<Antenna Reflector which Uses Artificial Magnet Conductor>

As described in FIG. 2, the artificial magnet conductor **10** according to the present embodiment reflects the electromagnetic wave which is emitted from the antenna substrate **300**, in an antenna device and emits the electromagnetic wave toward an emission direction of the electromagnetic wave of a directional antenna device. The artificial magnet conductor **10** according to the present embodiment is used as a reflection plate which reflects the electromagnetic wave.

The antenna reflector is mainly configured by the supporting body **200**. The reflection plate of the artificial magnet conductor **10** is provided such that the reflection plate of the artificial magnet conductor **10** can be detached from the supporting body **200**. That is, in the present embodiment, ends of the sides, which face each other, of the artificial magnet conductor **10** are inserted into the slits **202**, and thereby, the artificial magnet conductor is provided so as to face to the antenna substrate **300**.

According to the present embodiment, the ends of the sides, which face each other, of the artificial magnet conductor **10** are inserted and fixed, and thus, the artificial magnet conductor **10** is configured to be detachable, and can be attached or detached depending on whether or not the antenna have directivity.

In addition, the artificial magnet conductor of the related art is not able to obtain frequency characteristics with higher accuracy than the design value, and thus, the frequency characteristics greatly deviates due to an error of disposition when being attachable or detachable.

However, according to the present embodiment, the artificial magnet conductor **10** having frequency characteristics with high accuracy corresponding to the design value is used as a reflection plate, and thus, it is possible to obtain frequency characteristics with higher accuracy than the artificial magnet conductor of the related approximation ray theory, although being attachable or detachable.

In addition, according to the present embodiment, the artificial magnet conductor is used for the reflection plate, and thus, the antenna reflector to which the reflection plate is attachable or detachable can be minimized, and the antenna device itself can be minimized.

FIG. 18 is a radiation pattern diagram illustrating directivity when the artificial magnet conductor 10 which is produced in correspondence with 2.45 GHz is used as the reflection plate. In FIG. 18, an antenna pattern of an azimuth angle is denoted by polar coordinates, and an axis in a diameter direction of a ring denotes antenna gain (dBi). A reflection surface of the artificial magnet conductor 10 in FIG. 1 is perpendicular to a z direction, and thus, FIG. 18 illustrates an antenna pattern on an YZ plane.

A solid line denotes an emission pattern in a case where the artificial magnet conductor 10 according to the present embodiment is used as the reflection plate (HP: horizontal polarization, that is, a case of horizontal polarization). It can be seen that strength of a main lobe is greater than those of a back lobe and a side lobe, the reflector efficiently reflects the electromagnetic wave of 2.45 GHz, and the antenna device has directivity. A dashed line denotes the emission pattern in a case where the artificial magnet conductor 10 according to the present embodiment is used as the reflection plate (VP: vertical polarization, that is, a case of vertical polarization). The strength increases overall, compared to a case of a solid line, but it can be seen that the strength of the main lobe is greater than those of the back lobe and the side lobe, the reflector efficiently reflects the electromagnetic wave of 2.45 GHz, and the antenna device has directivity, in the same manner as in a case of the solid line.

Meanwhile, an alternate long and short dash line denotes an emission pattern in a case of deviating the reflection plate (a case of HP). It can be seen that each of the main lobe, the back lobe, and the side lobe has the same strength, the reflector reflects the electromagnetic wave of 2.45 GHz in all directions, and the antenna device does not have directivity. An alternate long and two short dashes line denotes an emission pattern in a case of deviating the reflection plate (a case of VP). It can be seen that each of the main lobe, the back lobe, and the side lobe has the same strength, the reflector reflects the electromagnetic wave of 2.45 GHz in all directions, and the antenna device does not have directivity, in the same manner as the alternate long and short dash line.

FIG. 19 is a radiation pattern diagram illustrating directivity of the antenna in a case where the artificial magnet conductor 10 (AMC, complete magnetic conductor) which is produced in correspondence with 2.45 GHz is used as the reflection plate, and in a case where a complete magnetic conductor (PEC) such as copper is used as the reflection plate. In FIG. 19, an antenna pattern of an azimuth angle is denoted by polar coordinates, and an axis in a diameter direction of a ring denotes antenna gain (dBi), in the same manner as in FIG. 18. A reflection plane of the artificial magnet conductor 10 in FIG. 1 is perpendicular to the z direction, and thus, FIG. 19 illustrates the antenna pattern on the YZ plane.

A solid line denotes the emission pattern in a case where the artificial magnet conductor 10 according to the present embodiment is used as a reflection plate (a case of horizontal polarization). A dashed line denotes the emission pattern in a case where the artificial magnet conductor 10 according to the present embodiment is used as the reflection plate (a case of vertical polarization). It can be seen from the solid line and the dashed line that strength of a main lobe is greater

than that of a back lobe, the reflector efficiently reflects the electromagnetic wave of 2.45 GHz, and the antenna device has directivity.

Meanwhile, an alternate long and short dash line denotes an emission pattern in a case where the complete electric conductor according to the present embodiment is used as the reflector (a case of HP). An alternate long and two short dashes line denotes an emission pattern in a case where the complete electric conductor is used as the reflector (a case of VP). It can be seen from the alternate long and short dash line and the alternate long and two short dashes line that strength of a main lobe is greater than that of a back lobe, but a ratio between the main lobe and the side lobe is less than a ratio in a case when the artificial magnet conductor 10 according to the present embodiment is used as the reflection plate.

Hence, in a case where the artificial magnet conductor 10 according to the present embodiment is used, it is possible to increase emission directivity of the electromagnetic wave of 2.45 GHz, compared to a case where the complete electric conductor of the related approximation ray theory is used. In addition, in a case where the complete electric conductor of the related art is used as the reflection plate, a separated distance between the antenna substrate and the reflection plate needs to be 30 mm or more, and in a case where the artificial magnet conductor 10 according to the present embodiment is used, the separated distance is approximately 15 mm. Accordingly, it is possible to minimize the antenna device more than that of the related art.

FIG. 20 is a view illustrating concept of obtaining a phase change amount between an incident wave and a reflected wave of the artificial magnet conductor according to the present invention. In FIG. 20, FIG. 20(a) illustrates a front surface 12S of the dielectric substrate 12 in a planar view. In addition, FIG. 20(b) is a cross-sectional view taken along line XXB-XXB in the artificial magnet conductor of FIG. 20(a). As illustrated in FIG. 20, the FSS (Frequency Selective Surface) 11 in which the basic cells 100 are periodically arranged in a matrix is formed on the front surface 12S of the dielectric substrate 12. Here, the basic cell 100 is configured with the patch 101 which is a patch pattern, and the loop 102 which is a loop pattern that is formed to have a predetermined gap (distance g) with the patch 101. In addition, the ground plate 13 (conductive film) that is a conductive film formed to overlap a region in which the basic cells 100 are arranged in a planar view is formed on a rear surface 12R of the dielectric substrate 12.

In the present invention, when the thickness d of the dielectric substrate 12 is obtained, a phase change from the incident wave toward the reflected wave with respect to the dielectric substrate 12 is obtained as an addition value which is obtained by adding the phase change ϕ_g (first phase change) in the gap of the distance g to the phase change amount ϕ_e (second phase change) between the basic cell 100 and the ground plate 13 (conductive film) in the dielectric substrate 12. In addition, the thickness d of the dielectric substrate 12 is calculated by a predetermined expression (for example, expression (23)), based on the obtained addition value.

That is, FIG. 20(b) illustrates a correspondence relationship between the phase change ϕ_g (first phase change) and the phase change amount ϕ_e (second phase change). As previously described, the phase change (addition value) of the reflected wave from the artificial magnet conductor 10 is a numeric value which is obtained by adding the phase change ϕ_g (first phase change) caused by the capacitance C_g which is formed by the gap (distance g) between the loop

101 and the loop 102, to the phase change amount ϕ_e (second phase change) based on the thickness d of the dielectric substrate 12. The phase change ϕ_g (first phase change) occurs as the evanescent wave generated by a pattern of inductive reactance is transferred to capacitive pattern through the capacitance C_g .

In FIG. 20(b), for example, in a case where the electromagnetic wave (incident wave) which is incident on the artificial magnet conductor 10 is 2.45 GHz, the loop 102 has inductive reactance, and the patch 101 has capacitive reactance. Accordingly, the evanescent wave is generated by the loop 102, and is transferred to the patch 101 through the capacitance C_g between the patch 101 and the loop 102.

Meanwhile, in a case where the electromagnetic wave (incident wave) which is incident on the artificial magnet conductor 10 is 5.44 GHz, the patch 101 has inductive reactance, and 102 has capacitive reactance. Accordingly, the evanescent wave is generated by the patch 101, and is transferred to the loop 102 through the capacitance C_g between the patch 101 and the loop 102.

Even in a case where the incident wave is either 2.45 GHz or 5.44 GHz, the evanescent wave which is generated by the pattern of inductive reactance is transferred to the capacitive reactance through the capacitance C_g , and thereby the phase change ϕ_g (first phase change) which occurs is the same as each other.

In addition, the phase change ϕ_g (first phase change) occurs depending on a distance in which the evanescent wave is transferred between the pattern 102 and the pattern 102, in the FSS (Frequency Selective Surface) 11. Thereafter, the evanescent wave is incident on the dielectric substrate 12 from the pattern 101, and is reflected by an interface between the dielectric substrate 12 and the ground plate 13 (conductive film), and the phase rotation amount ϕ_e (second phase change) depending on the thickness d of the dielectric substrate 12 occurs. That is, the phase rotation amount ϕ_e (second phase change) is a phase change which occurs between the basic cell 100 and the ground plate 13 (conductive film). Hence, the phase change from the incident wave toward the reflected wave is a numeric value which is obtained by adding the phase change ϕ_g (first phase change) to the phase rotation amount ϕ_e (second phase change). Hence, in the present invention, the phase rotation amount ϕ_e (second phase change) which is a phase change amount based on the thickness d of the dielectric substrate 12 is obtained by subtracting the phase change ϕ_g (first phase change) from the phase change from the incident wave toward the reflected wave with respect to the dielectric substrate 12 that is obtained as the addition value, and the thickness d of the dielectric substrate 12 is calculated by a predetermined expression (for example, expression (23)).

In the example of FIG. 20, the ground plate 13 is formed as a conductive film, but the ground plate 13 is not limited to a conductive film. That is, the ground plate 13 may be formed as a conductive layer.

The dielectric substrate 12 may be a medium which configures a conductor, and may use a conductive medium, such as an ABS resin, aluminum oxide (commonly known as alumina), or ceramics.

Processing of designing the artificial magnet conductor may be performed by recording a program for executing expression processing of designing the artificial magnet conductor according to the present invention in a computer readable recording medium, reading the program recorded in the recording medium into a computer system, and executing the program. Here, it is assumed that the "computer system" includes hardware such as OS or a peripheral

device. In addition, it is assumed that the "computer system" includes a WWW system which includes home page providing environment (or display environment). In addition, the "computer readable recording medium" is a recording medium, for example, a portable medium, such as a flexible disk, a magneto-optical disk, a ROM, or a CD-ROM, a hard disk which is embedded in the computer system, or the like. Furthermore, it is assumed that the "computer readable recording medium" includes an apparatus which retains a program for a predetermined time, such as a server in a case where a program is transmitted through a network such as Internet or a communication line such as a telephone line, or a volatile memory (RAM) embedded in a computer system which is a client.

In addition, the program may be transferred from a computer system including a storage device or the like to which the program is stored to another computer system through a transfer medium or by a carrier wave in the transfer medium. Here, the "transfer medium" which transfers the program indicates a medium having a function of transferring information, such as, a network such as Internet, or a communication line such as a telephone line. In addition, the program may be means for performing a part of the aforementioned function. Furthermore, the program may be means for performing the aforementioned function by combining the function with a program stored in the computer system, that is, a differential file (differential program).

The present application is based upon the Japanese Patent Application No. 2014-115956; filed on Jun. 4, 2014; the contents of which are incorporated herein by reference.

The invention claimed is:

1. An artificial magnet conductor comprising:
a dielectric medium;
basic cells, each being formed on a side of a front surface of the dielectric medium, and including a conductive patch pattern and a conductive loop pattern that is formed with a predetermined gap with the conductive patch pattern;
a frequency selective surface on which the basic cells are periodically arranged on the front surface of the dielectric medium; and
a conductive layer that is formed on a side of a rear surface of the dielectric medium, wherein
a phase change from an incident wave to a reflected wave with respect to the dielectric medium is set as an addition value in which a first phase change in the gap is added to a second phase change between the basic cell of the dielectric medium and the conductive layer, and a thickness of the dielectric medium is set based on the addition value, and

25

the thickness of the dielectric medium is greater than a distance of the gap when the thickness is calculated.

2. The artificial magnet conductor according to claim 1, wherein the dielectric medium is a dielectric substrate.

3. The artificial magnet conductor according to claim 1, wherein the thickness of the dielectric medium is set by a predetermined expression using the addition value.

4. The artificial magnet conductor according to claim 1, wherein the addition value is an addition phase change amount in which the second phase change which is a phase rotation amount is added to the first phase change caused by capacitance which is formed by the gap.

5. The artificial magnet conductor according to claim 3, wherein the predetermined expression is an expression that subtracts the first phase change from a phase change amount which is obtained based on an S parameter of the frequency selective surface and is required for the dielectric medium, calculates the second phase change which is obtained as the subtraction results, and calculates the thickness of the dielectric medium from the second phase change.

6. The artificial magnet conductor according to claim 1, wherein the frequency selective surface is formed such that one of the conductive patch pattern and the conductive loop pattern has inductive reactance, and the other has capacitive reactance, at a predetermined frequency bandwidth.

7. The artificial magnet conductor according to claim 1, wherein the thickness of the dielectric medium is set such that the artificial magnet conductor has frequency characteristics corresponding to a plurality of frequencies, change curves of a dielectric thickness and a phase in each of the plurality of frequencies are obtained, and the phase is within $\pm 45^\circ$ of the entirety of the plurality of frequencies.

8. The artificial magnet conductor according to claim 1, wherein the conductive patch pattern is formed in a polygon, and

the frequency characteristics of the frequency selective surface are adjusted by further increasing the number of apexes by cutting regions of apex portions of the polygon in a direction perpendicular to a line connecting the apexes to a center of the polygon.

9. An antenna reflector comprising:

the artificial magnet conductor according to claim 1, which is used as a reflection plate.

10. The antenna reflector according to claim 9, wherein the artificial magnet conductor is provided to be detachable.

11. A method for calculating a thickness of a dielectric medium of an artificial magnet conductor including a dielectric medium; basic cells, each being formed on a side of a front surface of the dielectric medium, and including a conductive patch pattern and a conductive loop pattern that is formed with a predetermined gap with the conductive patch pattern; a frequency selective surface on which the basic cells are periodically arranged on the front surface of

26

the dielectric medium; and a conductive layer that is formed on a side of a rear surface of the dielectric medium, the method comprising:

setting a phase change from an incident wave to a reflected wave with respect to the dielectric medium, as an addition value in which a first phase change in the gap is added to a second phase change between the basic cell of the dielectric medium and the conductive layer; and

calculating the thickness of the dielectric medium based on the addition value,

wherein the thickness of the dielectric medium is greater than a distance of the gap when the thickness is calculated.

12. The method according to claim 11, wherein the dielectric medium is a dielectric substrate.

13. The method according to claim 11, wherein the thickness of the dielectric medium is set by a predetermined expression using the addition value.

14. The method according to claim 11, wherein the addition value is an addition phase change amount in which the second phase change which is a phase rotation amount is added to the first phase change caused by capacitance which is formed by the gap.

15. The method according to claim 13, wherein the predetermined expression is an expression that subtracts the first phase change from a phase change amount which is obtained based on an S parameter of the frequency selective surface and is required for the dielectric medium, calculates the second phase change which is obtained as the subtraction results, and calculates the thickness of the dielectric medium from the second phase change.

16. The method according to claim 11, wherein the frequency selective surface is formed such that one of the conductive patch pattern and the conductive loop pattern has inductive reactance, and the other has capacitive reactance, at a predetermined frequency bandwidth.

17. The method according to claim 11, wherein the thickness of the dielectric medium is set such that the artificial magnet conductor has frequency characteristics corresponding to a plurality of frequencies, change curves of a dielectric thickness and a phase in each of the plurality of frequencies are obtained, and the phase is within $\pm 45^\circ$ of the entirety of the plurality of frequencies.

18. The method according to claim 11, wherein the conductive patch pattern is formed in a polygon, and the frequency characteristics of the frequency selective surface are adjusted by further increasing the number of apexes by cutting regions of apex portions of the polygon in a direction perpendicular to a line connecting the apexes to a center of the polygon.
